UNITED STATES PATENT OFFICE.

AUGUSTUS S. HENSHAW, OF BROOKLYN, NEW YORK.

SUSPENDER-FASTENER.

SPECIFICATION forming part of Letters Patent No. 694,857, dated March 4, 1902.

Application filed February 5, 1901. Serial No. 46,081. (No model.)

To all whom it may concern:

Be it known that I, AUGUSTUS S. HENSHAW, a citizen of the United States, residing at Brooklyn, in the county of Kings and State of New York, have invented a new and useful Suspender-Fastener, of which the following is a specification.

This invention relates to improvements in suspender-fasteners; and the object is to provide a simple and improved fastener for attaching the suspenders to the waistband of the trousers, said fastener being carried permanently by the suspenders and so constructed that it may be readily attached to or removed from the trousers and when attached thereto firmly engage the same without slipping or becoming accidentally disengaged therefrom and without tearing or injuring the trousers in any way.

With the above objects in view the invention consists in the novel features of construction hereinafter fully described, particularly pointed out in the claims, and clearly illustrated by the accompanying drawings, in which—

Figure 1 is a perspective view showing my invention in operation, a portion of the trousers-band and suspender-tab being shown. Fig. 2 is a sectional view taken transversely through the fastener, the suspender-tab, and the waistband; and Fig. 3 is a perspective view of the clasp detached from the waistband and the suspender-tab.

Referring now more particularly to the accompanying drawings, A designates the body of my fastener, which is bent to substantially U shape, the edge of one of the legs thereof being formed upon its inner side with a plurality of inwardly and slightly upwardly extending teeth or tangs B. The other leg of the body A is formed intermediately of its ends with a transversely-extending slot C, the ends of which terminate in inwardly-projecting perforated ears a. A clamping member is pivotally held in said slot C, said member having an inwardly-extending clamping portion or plate D, the ends of which are provided with pintles that engage the ears a and an outwardly-extending slightly-curved fin-

ger portion E, which is disposed at an angle 50 to the clamping portion D.

The suspender-tabs F carry on their lower ends loops G, which are extended through the U-shaped fastener and between the legs thereof, loosely connecting the fastener to the 55 tab.

In operation the fastener is applied to the trousers-band, the legs thereof straddling said band. The finger portion E is then pressed downwardly, which raises the clamp- 60 ing portion D of the clamping chamber, causing the same to press against the opposite side of the waistband from that upon which the teeth or tangs B are positioned, so that the material of the waistband is forced into said 65 teeth and the suspender-tab thus securely attached to the band.

The fastener may be positioned upon the band either with the clamping member upon the outer side of said band or upon the inner 70 side thereof, as may be desired, the device presenting a much neater appearance with the clamping member upon the inner side and being much more convenient in operation with the clamping member upon the 75 outer side.

It will of course be understood that each suspender-tab carries one of the fasteners and that said fasteners may be ornamented as may be desired, so as to present a neat and 80 attractive appearance.

By the use of my improved fastener suspender-buttons upon the trousers-band are dispensed with, and therefore all of the inconvenience incident to the breaking or tearing of the same is obviated, the fastener being always at hand for being quickly attached to or detached from the trousers-band.

Having thus fully described my invention, what I claim as new, and desire to secure by 90 Letters Patent, is—

As an improved article of manufacture, a suspender-fastener consisting of a metallic plate bent centrally upon itself, one edge of the plate being turned inwardly and serrated 95 or toothed, the opposing member of the plate being slotted transversely and provided with inwardly-projecting integral perforated lugs

or ears at the ends of the slot, the angular clamping member having integral trunnions or pivots which fit in the perforated ears or lugs, the outer portion of said angular clamping member being adapted to be turned down upon the side of the main plate, and the loop by means of which the fastener is connected

to the end of the suspender, substantially as shown and described.

AUGUSTUS S. HENSHAW.
